PRINTING PLATE SHAVING MACHINE

Lee C. Hammond, Donald E. Sutton, and Adrian L. Vander Linde, Kalamazoo, and Edward C. Krueger, Otsego, Mich., assignors to Hammond Machinery Builders, Inc., Kalamazoo, Mich.

Application May 31, 1951, Serial No. 229,134

8 Claims. (Cl. 90—25)

1

This invention relates to improvements in a printing plate shaving machine for large and small plates.

The principal objects of this invention are:

First, to provide a machine for shaving the backs of printing plates which may vary in size from large full page newspaper plates to small insert plates commonly referred to as thumb nail plates.

Second, to provide a plate shaving machine with hold-down elements which will prevent the tilting or cocking of small plate inserts as they are passed underneath the shaving knife.

Third, to provide a shaving machine with a holder for small plate inserts that will advance one or more inserts against the shaving knife in the same manner that full page plates are advanced and shaved.

Fourth, to provide a hold-down shoe for a plate shaving machine that is movable to operative position closely adjacent the front edge of the knife to hold down small plates and to raised inoperative position when the machine is used to shave large page plates.

Fifth, to provide a shaving machine with a plate hold-down roller that is connected to a cut-out switch to automatically stop the machine in case a deformed plate is attempted to be forced through the machine.

Sixth, to provide a holder in the form of a flat plate that can be supported on the table of a shaving machine to simultaneously advance a plurality of small plate inserts through the machine.

Other objects and advantages relating to our invention will be apparent from a consideration of the following description and claims, the drawings of which there are three sheets illustrate a practical and preferred form of our invention.

Fig. 1 is a perspective view of our machine with the small plate holder and a plurality of small plate inserts in position thereon.

Fig. 2 is a fragmentary front elevational view of the cross head of the machine and the front hold-down roller, the view being partially in section along the plane of the line 2—2 in Fig. 3.

Fig. 3 is a vertical longitudinal cross sectional view through the cross head and table of the machine taken along the planes of the broken line 3—3 in Fig. 2.

Fig. 4 is a fragmentary plan view of the small plate holder.

Fig. 5 is an enlarged fragmentary vertical cross sectional view showing the small plate holder and a plurality of small plate inserts therein op-

2

eratively associated with the small plate hold-down and blade of the shaver.

The machine in which our invention is incorporated includes a suitable base 1 on which a generally rectangular body 2 is supported. The body is shaped and constructed to provide slideways 3 which may be considered as extending longitudinally from end to end of the body. Slidably mounted in the ways 3 is a table 4, the table having V-shaped ways 5 formed along its side edges to coat with the ways 3. Desirably ball bearings not illustrated interconnect the ways 3 and 5. Columns 6 projecting vertically upwardly from each side of the ways 3 support a cross head 7 which is vertically adjustable on the columns by the manipulation of a hand wheel 8 and associated adjusting mechanisms which form no part of the present invention. The cross head 7 carries a transversely extending knife 9 (see Fig. 3) having a hardened cutting edge 10 on its lower front side which is thus adapted to be present at different elevations transversely to the path of travel of the table 4. The knife extended transversely along the cross head 7 at least across the full width of the table 4. The left end of the table 4 is provided with a stop bar or abutment 11 projecting above the surface of the table to engage the edge of a printing plate and force the plate into shaving engagement with the knife 9 as the table is advanced to the right by driving means enclosed in the machine.

The ends of the crosshead 7 are provided with vertically adjustable depending posts 12 at each end of the head and these posts serve as supports for a front holdown shaft 13. Intermediate of its ends, the shaft 13 extends through the lower bifurcated ends of a fork member 14 as is most particularly illustrated in Fig. 2. Bushings 15 pressed into a short center roller 16 and the ends of the two long side rollers 17 rotatably support the rollers on the shaft. Toward the ends of the shaft 13 there are provided a pair of arms 18 and 19 which are non-rotatably secured to the shaft 13 by pins 20. Short end rollers 21 extend between the arms 18 and 19 and the posts 12. The function of the arms 18 and 19 will be described presently.

The head 7 is of heavy chambered construction having a bottom wall 22. The upper end or stem 50 of the fork member 14 projects slidably upwardly through the wall 22 as at 23 to act as a tappet for actuating a lever 24 pivotally supported at 25. The opposite end of the lever is positioned to actuate an electric switch 26 of the small movement type and the switch is connected by well

known means in the power circuit of the machine to interrupt the operation of the shaver when excessive pressure on the middle of the hold-down rollers deflects the shaft 13 and the fork member 14 upwardly. A compression spring 27 is adjustably compressed between the wall 22 and the top of the bifurcated head of the fork member 14 to determine the pressure required to actuate the switch 26.

With particular reference to Fig. 3 it will be noted that the hold-down shaft 13 is spaced substantially in front of the blade 10 and that the arm 19 has a wedge-like rearward projection 28 which extends beyond the contour or circumference of the rolls 17 and 21. The left arm 18 has a similar rearward projection. Fixedly connected between the projections on the arms 18 and 19 and extending transversely across the table therebetween is a wedge shaped hold-down shoe 29, the lower edge of which is parallel and tangent to the lower edge of the hold-down rollers when the arms 18 and 19 are upright. The rear edge of the hold-down shoe 29 extends to closely adjacent to the front edge of the knife 9. In this position of the hold-down shoe 29 small insert printing plates which are advanced by the table 4 underneath the front hold-down rollers will have no opportunity to tilt upwardly and cock as their leading edges pass out from underneath the front hold-down rolls so that the inserts will be properly and accurately advanced against the cutting edge 10 of the knife. The arms 18 and 19 and the hold-down shoe 29 are adjustably held in relation to the head 7 by means of a crank arm 30 secured to a rock shaft 31. The shaft 31 is horizontally pivotally supported in a bearing bracket 32 bolted to the front side of the right end of the head 7. A pin 33 carried on the swinging end of the arm 30 engages a slot 34 in the right arm 19 on the hold-down shaft to rock the arm 19 and hold-down shoe 29 between the operative position shown in full lines and the inoperative position in dotted lines in Fig. 3. A shim 35 positioned between the vertical surface of the head and the bearing bracket 32 permits the shaft 31 and pin 33 to be adjusted relative to the head so that the under surface of the shoe 29 is horizontal in the operative position of the arms and rock shaft. A hand operative lever 36 is provided for actuating the rock shaft, and desirably spring pressed detent stops 37 are provided between the arm 30 and the bearing bracket 32 to locate the arm and operating lever in their two adjusting positions. Coacting with the hold-down shoe 29 in holding the small plate inserts in correct position relative to the knife 9 is a rear hold-down shoe 38 which is clamped between the blade 9 and the cross head behind the cutting edge 10. The rear hold-down shoe 38 is adjusted until its lower edge is parallel to and slightly above the cutting edge of the knife so that after a small plate insert has passed underneath the cutting edge and been shaved to the proper thickness, it will be held down by the shoe 38 and prevented from tilting upwardly at its leading edge due to pressure of the cutting edge of the knife on the trailing portion of the insert. Rear hold-down rollers 39 are carried by the head 7 behind the shoe 38 to further hold the newly shaved plates against the table and in proper flat position with respect to the cutting edge of the knife. The shoe 29, rear shoe 38 and rear hold down rollers 39 being carried by the cross head 7 are all vertically adjustable with respect to the work and are

fixed relative to the blade 9 so that the plates being shaved, large or small, are properly oriented with respect to the blade.

In order to effectively utilize the ability of the machine to advance small plate inserts underneath the knife 9 we have provided a small plate holder in the form of a flat sheet 40 of relatively stiff rigid metal such as steel. The plate 40 is provided with a forwardly beveled trailing edge 41 which coacts with the stop bar 11 on the table to advance the sheet with the table. The body of the sheet is apertured or slotted in a plurality of obliquely arranged slots 42 desirably arranged in forwardly converging pairs as illustrated. The rear corners of the slots 42 are formed as circular holes 43 embracing the intersection of the side edges of the slots so that accurately rectangular small plate inserts 44 can be snugly and accurately seated in the trailing corners of the slots. The sheet 40 is thinner than the thinnest printing plate to be shaved on the machine so that the small plate inserts project upwardly above the surface of the sheet as is best illustrated in Fig. 5. In this position the small plate inserts with their irregular printing surfaces 45 facing downwardly will advance with the table and sheet underneath the hold-down shoe 29 and against the cutting edge of the knife to shave the inserts to uniform thickness. As previously described, the hold-down shoes 29 and 38 will prevent the inserts from cocking while the oblique arrangement of the slots 42 prevents the inserts from moving horizontally in the sheet 40. So long as the adjacent sides of the inserts are squared, additional inserts can be fitted into the slots 42 like blocks so that a great many of the inserts can be shaved to the same thickness by one single pass of the table and sheet underneath the shaving blade 9. A large rectangular hold down frame is shown pivoted to the back side of the body 2 in Fig. 1. This is adapted to be clamped down over the path of the table 4 and a plate being advanced thereby to the knife to prevent the plate from buckling. No novelty is claimed in the hold down frame so its construction is not described in detail.

Should one or more of the small plate inserts be abnormally thick it will deflect the front hold-down rollers and shaft sufficiently to actuate the switch 26 as previously described to prevent damage to the machine or to the inserts. The protective function of the switch 26 is equally effective when shaving large page size plates on the machine.

Having thus described our invention, what we claim as new and desire to secure by Letters Patent is:

1. In a printing plate shaving machine having a translatable table with a vertically adjustable head extending transversely across the path of said table, the combination of a shaving knife carried by said head to coact with printing plates on said table, a transversely extending shaft supported at its ends from said head in parallel relationship in front of said knife, a support for the center of said shaft extending slidably into said head, a spring biasing said support downwardly, an electrical switch connected to control the operation of said machine and positioned in said head to be opened by predetermined upward movement of said support, a longitudinally sectional front hold-down roller rotatably mounted on said shaft and having its lower edge at approximately the same level as the edge of said knife, arms non-rotatably secured to said shaft

and projecting thereabove, a front hold-down shoe of wedge shaped cross section supported by and extending transversely between said arms across said table and between the periphery of said roller and said knife, crank means mounted on said head and connected to one of said arms to swing said shoe into operative position with its lower surface lying approximately in the plane of the bottom of said roller and the edge of said knife, a plate-like rear hold-down shoe clamped between the lower portion of said knife and said head behind said knife and with its lower edge approximately level with the cutting edge of said knife, and a small plate holding sheet adapted to be supported and advanced by said table in clearing relation underneath said knife and said shoes, said sheet having a plurality of rectangularly squared obliquely arranged slots formed therein in forwardly converging pairs to receive and hold small plate inserts, the rear corners of said slots being outwardly rounded to embrace the intersections of the rear edge lines of the slots.

2. In a printing plate shaving machine having a translatable table with a vertically adjustable head extending transversely across the path of said table, the combination of a shaving knife carried by said head to coact with printing plates on said table, a transversely extending shaft supported at its ends from said head in parallel relationship in front of said knife, a support for the center of said shaft extending slidably into said head, a spring biasing said support downwardly, an electrical switch connected to control the operation of said machine and positioned in said head to be opened by predetermined upward movement of said support, a longitudinally sectional front hold-down roller rotatably mounted on said shaft and having its lower edge at approximately the same level as the edge of said knife, arms pivotally supported by said shaft and projecting thereabove, a front hold-down shoe supported by and extending transversely between said arms across said table and between the periphery of said roller and said knife, crank means mounted on said head and connected to one of said arms to swing said shoe into operative position with its lower surface lying approximately in the plane of the bottom of said roller and the edge of said knife, and a plate-like rear hold-down shoe clamped between the lower portion of said knife and said head behind said knife and with its lower edge approximately level with the cutting edge of said knife.

3. In a printing plate shaving machine having a translatable table with a vertically adjustable head extending transversely across the path of said table, the combination of a shaving knife carried by said head to coact with printing plates on said table, a transversely extending shaft supported at its ends from said head in parallel relationship in front of said knife, a front hold-down roller rotatably mounted on said shaft and having its lower edge at approximately the same level as the edge of said knife, arms pivotally supported by said shaft and projecting thereabove, a front hold-down shoe supported by and extending transversely between said arms and between the periphery of said roller and said knife, crank means mounted on said head and connected to one of said arms to swing said shoe into operative position with its lower surface lying approximately in the plane of the bottom of said roller and the edge of said knife, and a small plate holding sheet adapted to be supported

and advanced by said table in clearing relation underneath said knife and said shoe, said sheet having a rectangularly squared obliquely arranged slot formed therein to receive and hold small plate inserts.

4. A crosshead for a printing plate shaving machine comprising, end upright portions, a knife abutment extending between said end portions and disposed toward the rear of said end portions, a shaving knife adjustably secured to said abutment with its lower cutting edge disposed forwardly, a plate-like rear hold-down shoe clamped between said knife and said abutment with its lower edge approximately level with the cutting edge of said knife, a shaft extending between said end portions forwardly of said knife, arms pivotally supported by said shaft toward each end thereof, a front hold-down shoe of wedge shaped cross section extending transversely between said arms and swingable therewith to locate its under surface approximately level with the cutting edge of said knife and closely adjacent thereto, lever means carried by one of said end portions for tilting one of said arms on said shaft, and front hold-down rollers rotatably mounted on said shaft between said arms with the periphery of the rollers approximately tangent to the plane of the lower face of said front hold-down shoe.

5. A crosshead for a printing plate shaving machine comprising, end upright portions, a knife abutment extending between said end portions and disposed toward the rear of said end portions, a shaving knife adjustably secured to said abutment with its lower cutting edge disposed forwardly, a shaft extending between said end portions forwardly of said knife, arms pivotally supported by said shaft toward each end thereof, a front hold-down shoe extending transversely between said arms and swingable therewith to locate its under surface approximately level with the cutting edge of said knife and closely adjacent thereto, lever means carried by one of said end portions for tilting one of said arms on said shaft, and front hold-down rollers rotatably mounted on said shaft between said arms with the periphery of the rollers approximately tangent to the plane of the lower face of said front hold-down shoe.

6. A crosshead for a printing plate shaving machine comprising, end upright portions, a knife abutment extending between said end portions and disposed toward the rear of said end portions, a shaving knife secured to said abutment with its lower cutting edge disposed forwardly, a plate-like rear hold-down shoe clamped between said knife and said abutment with its lower edge approximately level with the cutting edge of said knife, a shaft extending between said end portions forwardly of said knife, arms pivotally supported by said shaft toward each end thereof, a front hold-down shoe extending transversely between said arms and swingable therewith to locate its under surface approximately level with the cutting edge of said knife and closely adjacent thereto, and lever means carried by one of said end portions for tilting one of said arms on said shaft.

7. A crosshead for a printing plate shaving machine comprising, end upright portions, a knife abutment extending between said end portions and disposed toward the rear of said end portions, a shaving knife secured to said abutment with its lower cutting edge disposed forwardly, a shaft extending between said end portions for

wardly of said knife, arms pivotally supported by said shaft toward each end thereof, a front hold-down shoe extending transversely between said arms and swingable therewith to locate its under surface approximately level with the cutting edge of said knife and closely adjacent thereto, and lever means carried by one of said end portions for tilting one of said arms on said shaft.

8. A crosshead for a printing plate shaving machine comprising, end upright portions, a knife abutment extending between said end portions and disposed toward the rear of said end portions, a shaving knife secured to said abutment with its lower cutting edge disposed forwardly, a rear hold-down shoe clamped between said knife and said abutment with its lower edge approximately level with the cutting edge of said knife, means for removably supporting a front hold-down shoe transversely between said end portions with its under surface approximately level with the cutting edge of said knife and

5 closely adjacent thereto, and a front hold-down roller rotatably mounted between said end portions with the periphery of the roller approximately tangent to the plane of the lower face of said front hold-down shoe.
